ATION OF MAINE.

BUILDER MECHANISM FOR SPINNING-MACHINES.

1,201,583.

Specification of Letters Patent. Patented Oct. 17, 1916.

Application filed August 14, 1916. Serial No. 114,678.

To all whom it may concern:

Be it known that we, HARRY F. HAWKINS and MYRON L. STICKNEY, both citizens of the United States, residing at Manchester, county of Hillsborough, State of New Hampshire, have invented an Improvement in Builder Mechanism for Spinning-Machines, of which the following description, in connection with the accompanying drawing, is a specification, like characters on the drawing representing like parts.

This invention relates to improvements in builder mechanism for spinning machines and its special purpose is to provide a form of mechanism by which the spinning machine may be adapted for winding different types of bobbins.

In that type of bobbin provided with a longitudinal slot in the barrel to receive a feeler it is desirable that a sufficient amount of filling be wound upon the base of the bobbin beneath that portion of the slot through which the feeler operates to enable a final pick to be made with such an anchorage of the filling upon the base of the bobbin as will insure the filling being caught by the usual temple thread cutter. This invention provides as in the case of our prior application Serial No. 69746 filed January 3, 1916 for winding this type of bobbin with a primary winding comprising one or more short slow traverses of filling in which the first traverse is a downward traverse commencing at a point below the portion of the slot through which the feeler operates.

In winding other types of bobbins to cooperate with other types of feelers it is necessary to form a "bunch" or primary winding made up of a comparatively large number of short slow traverses and in which the bunch tapers off at each end.

It is the main object of this invention to provide for winding both of these types of bobbins by a single mechanism which may be readily adjusted for either purpose. This materially increases the value of the spinning frame and renders unnecessary the duplication of spinning frames in mills where both types of bobbins are used.

The invention also provides more specifically a multiplying mechanism by which

the rotations of the primary cam are multiplied before the primary cam is thrown out of operation and the main or service winding begins. This multiplying mechanism 55 with its adjustments enables any desired number of traverses to be given during the primary winding.

The invention also more specifically provides a form of means for securing the actuation of the pick motion during the period of primary winding when the usual pick motion actuating means is out of range.

Other features of the invention and the nature thereof will more fully appear from 65 the following description and the accompanying drawings and will be pointed out in the annexed claims.

A preferred embodiment of the invention is disclosed herein as applied to a usual type 70 of ring spinning machine.

In the drawings, Figure 1 is a front view of a portion of a spinning machine embodying our invention; Fig. 2 is a right hand end elevation partially in cross section showing the multiplier and adjacent parts; Fig. 3 is a detail view in plan showing the dog which retains the primary cam in operative relation to the builder-arm; Fig. 4 is a detail view in elevation showing the dog which 80 retains in operative relation the device to engage and operate the pick motion during the control of the builder-arm by the primary cam; Fig. 5 is a detail chiefly in cross section showing the multiplier and its 85 mounting on the frame; Fig. 6 is a plan view of the mechanism for actuating the builder arm; Fig. 7 is a view of the cams and mechanism for operating the same taken on the line 7-7 of Fig. 6, and looking 90 toward the right, and a portion of the builder arm shown in dotted lines.

The mechanism which is illustrated is that of a familiar type of spinning frame having a form of construction embodying the present invention applied thereto. As has been pointed out one feature of the invention resides in providing such a construction of mechanism that the apparatus may be employed as desired either on the one hand for 100 winding a feeler slotted bobbin in such a manner as to leave the required amount of

filling on the bobbin after the action of the feeler has taken place, or on the other hand for winding an ordinary bobbin with a suitable tapered bunch. Thus one spinning apparatus is rendered capable of performing both kinds of work. But it will be obvious that the flexibility of use thus obtained somewhat complicates the construction so far as other features of the invention are concerned. If, for example the spinning frame were to be used only for winding feeler slotted bobbins then the construction provided in our prior patent above referred to would be sufficient while if the spinning frame were to be used only for winding ordinary bobbins with the desired tapered bunch then many of the features of construction embodying the invention might be simplified. But as it is desirable that the apparatus shall be fitted for either of these two functions the construction illustrated is selected as the preferred embodiment of the invention.

In the construction as shown the apparatus comprises the usual supporting frame 1 having the ladder 2 which supports a series of spindles 3 adapted to receive the bobbins or other filling carriers and which are driven by the whirls 4 in the usual manner. A lifter rail 5 having thereon the series of rings 6 with the usual travelers is supported upon a plurality of lifter rods 7 having at their lower ends suitable flat supporting members 8 resting upon rolls 9 adjustably supported upon the ends of counterweighted bell crank levers 10 pivoted at 11 in the brackets 12 depending from the underside of the ladder 2. The upright arms 13 of the bell crank levers are connected together by a rod 14 and the foremost of said arms is connected to a chain 15 which runs over an idler 16 to a drum 17 carried by the builder arm 18. The drum 17 is rotated through the worm gear 19 and a worm upon the shaft 20 by the usual ratchet 21 and pick pawl 22, the general operation of which is of a well known type, and the means for operating which during the primary traverse will be described later. The builder arm 18 may be of any usual type such as a lever pivotally mounted at one end 23, carrying the drum 17 and pick motion adjacent its opposite end, and provided intermediate its length with the laterally extending lug or follower 24 which is engaged and acted upon by the builder actuating cams. Inasmuch as the follower is essentially a part of the builder arm the cams may be considered as operating directly upon the builder arm.

The builder arm actuating mechanism illustrated comprises a bracket which for convenience is made in three sections having faces 25, 26 and 27, respectively, adapted to

be secured by both bolt and slot connections 65 28 to the underside of the ladder 2. The bracket section 25 is provided with downwardly and rearwardly extending arms 29 and 30. The arm 29 is provided with an extension secured thereto by bolts 31 and is 70 provided with a boss 32 which serves as one journal for the usual cam shaft 33, the other journal being in the frame 1. This shaft 33 is continuously driven in the usual manner.

Primary and auxiliary cams 34 and 35, respectively, are rotatably mounted upon the cam shaft 33 and are so connected as by pins 36 as to rotate in unison and yet be capable of separation. The cam 35 is provided with a laterally extending sleeve 37 80 surrounding the shaft 33 and terminating in a disk 38 provided with the clutch face 39, and upon the opposite side with the positioning pins 40 preferably corresponding in number to the lobes of the cam. 85

Rotation is transmitted to the cam shaft by the clutch 41, having a clutch face 42 complementary to the clutch face 39. This clutch 41 is provided with a laterally extending hub 43 and is slidably feathered on 90 the shaft 33. The hub 43 of the clutch is provided with an annular groove 44 engaged by the forked or yoke shaped end 45 of a shipper. The faces 39 of the disk and 42 of the clutch are normally maintained in contact by a helical spring 46 surrounding the shaft 33 and bearing at one end against the hub 43, and at the opposite end against a collar 47, adjustably secured on the shaft 33. 95

The shipper is provided with a hub 48 100 slidably mounted upon a shaft 49 which is journaled in the arms 29 and 30 of the bracket. The shipper is provided intermediate of its forked end and hub with an offset portion 50 in which is journaled an anti-friction roller 51 adapted to be engaged by the face of a cam 52 upon the end of an arm 53 having a hub 54 which is rigidly secured by the set screw 55 to the shaft 49. 105

The shaft 49 is rotated through a foot 110 lever 56 at the end of an arm 57 having a hub 58 rigidly secured by a set screw 59 to the shaft 49 and having the extension 60 provided with angularly disposed faces 61 and 62 adapted to engage the studs 40 upon 115 the disk 38 of the cam sleeve 37. This mechanism constitutes the cam releasing and setting mechanism whereby the cams are positioned in such a manner that the initial winding upon the filling carrier will start 120 at a predetermined position which in the case of the winding of a feeler slotted bobbin is such that the first movement of the builder arm affected by the primary cam will cause a downward traverse of yarn upon 125 the bobbin.

In the operation of this mechanism the depression of the foot lever 56 serves to rock

the shaft 49 about its axis causing the cam 52 on the arm 53 to engage the anti-friction roll 51 of the shipper and to slide the shipper longitudinally of the shaft 49 and toward the left, viewing Fig. 6, thus disengaging the clutch 41 from the disk 38. Further movement of the foot lever 56 brings one of the inclined faces 61 or 62 into engagement with one of the pins 40 rotating the disk 38 and with it the cams 34 and 35 until the other of the faces 61 or 62 engages another pin 40. These pins 40 are so disposed upon the disk 38 that when two pins are engaged by the faces 61 and 62 the cams will be positioned relatively to the builder arm so that the initial movement of the cam will cause a downward movement of the lifter rail. But by setting the pins 40 in the proper angular relation to the disk 38 the cams may be positioned relatively to the builder arm to begin the traverse at any required point.

When the cams have been set in the manner thus described the foot lever 56 is released and the spring 46 forces the clutch 41 into normal position causing the engagement of its face 42 with the face 39 of the disk 38 so that the cam will commence its actuation of the builder arm from the predetermined point at which the cam is set.

During the primary winding the builder arm is actuated by the primary traverse cam 34, the lobes of which it will be noted have a considerably less pitch than those of the secondary cam 35 so that when the primary cam 34 actuates the builder arm a comparatively short and slow traverse of winding upon the bobbin is effected.

The period during which the primary traverse cam shall actuate the builder arm depends upon the desired character of the traverse winding. When a feeler slotted bobbin is being wound such actuation is required only for a sufficient period to lay upon the bobbin enough yarn to produce a full pick across the loom with a slight excess to provide such an anchorage upon the base of the bobbin as will insure the yarn being caught by the usual temple thread cutter, and so insure that the end will not curl up within the shed. When an ordinary bobbin is to be wound with a bunch such actuation is required for a sufficient period to build the bunch to the required size involving a considerable number of traverses.

This invention presents a construction, a preferred form of which is illustrated herein, in which either of these primary windings may be secured, in which the traverse may begin at any desired point, and in which the number of traverses may be varied as required. The upper limit of the number of such primary traverses is in the specific construction illustrated sixty-four, but the prin-

ciple under which this construction operates 65 will readily be seen to be such that the number may be increased if required.

In any case upon the completion of the primary winding it is necessary to provide means for removing the primary traverse 70 cam 34 from its operative relation to the builder arm and for substituting therefor the secondary traverse cam 35 which operates to lay the main or service winding. This is accomplished in the construction 75 illustrated by providing means operable at a predetermined time to shift the primary cam axially of the cam shaft 33 at the completion of the primary winding leaving the secondary cam in operative contact with the 80 builder arm. In this construction spring actuated means are employed which normally act to move the primary cam 34 axially of the shaft 33 out of co-operative relation to the builder arm. The action of 85 this spring actuated means is controlled by a trip mechanism which in turn is shown as controlled from the cam itself. If, however, the primary cam acted directly to control the trip mechanism constructional requirements would place a limit upon the 90 number of primary traverses that could be laid before the actuation of the trip mechanism.

This invention as one feature introduces a 95 multiplier or multiplying mechanism which transmits the action of the primary cam to the trip mechanism and thus enables any required number of primary traverses to be laid and still permits the number to be determined by the action of the primary cam itself. The introduction of this multiplier or multiplying mechanism renders the apparatus extremely flexible as to the size of the primary winding and enables it to range 100 from the simple downward and upward traverse required in a feeler slotted bobbin to be used in a narrow loom up to as large a bunch as may be required in the winding 105 of any bobbin for use in automatic filling 110 replenishing looms.

The spring actuated means normally acting to move the primary cam out of co-operative relation with the builder arm comprises a rod 63 mounted to slide longitudinally in the arms 29 and 30 of the bracket 25 and provided with a helical spring 64 mounted upon the rod abutting at one end against the arm 29 and at the other end against a collar 65 adjustably secured to the 120 rod whereby the rod is normally projected toward the right, viewing Fig. 6. At the end opposite from the spring the rod 63 is forked at 66 and pivoted at 67 to a lever 68. This lever is pivotally mounted upon a stud 125 69 depending from the bracket section 27 and at its opposite lower end 70 is forked and provided with oppositely disposed studs

71 entering the annular groove 72 of the hub 73 which projects laterally from the primary cam 34. The normal action of the spring 64 through the parts thus described is therefore to force the primary cam away from the secondary cam out of contact with the builder arm and into the position shown, for example, in dotted lines in Fig. 6.

As the primary cam 34 is used in laying 10 the first or primary winding, means are provided operable concurrently with the cam setting mechanism to position the primary cam 34 in operative relation to the builder arm. For this purpose as illustrated 15 the shipper is provided with an extension 74 and a bifurcated end 75 embracing the rod 63 adjacent the collar 65 so that as the shipper is moved laterally toward the left, viewing Fig. 6, by the depression of the foot 20 lever 56 the bifurcated end 75 will engage the collar 65 and force the rod 63 to the left, thus oscillating the lever 68 about its pivot and forcing the primary cam 34 firmly against the secondary cam 35. The primary 25 cam is locked in this position in which it is in coöperative relation with the builder arm by a latch 76 having a hub 77 journaled on a pin or shaft 78 secured to and projecting laterally from the arm 30 of the bracket 30 25. A counterweight 79 acts normally to swing the lower end of the latch toward the rod 63 and into engagement with a dog 80 projecting laterally from a collar 81 adjustably secured to the rod 63. This dog 80 35 has its face beveled toward the left, viewing Fig. 6. When, therefore, in the setting and positioning operation the rod 63 is moved toward the left to position the primary cam 34 the beveled face of the dog 80 40 pushes back the latch 76, and when the required position is reached the latch 76 drops by gravity behind the dog 80 thus locking the rod in position.

The tripping mechanism of which the 45 latch is a part is operated from the primary cam so that at the conclusion of a predetermined extent of primary winding the primary cam will operate the tripping mechanism which will then release the spring actuated rod 63 causing it to move the primary cam out of coöperation with the builder arm, and as will appear, bring the secondary cam into coöperative relation with the builder arm and initiate the main or 50 service winding. But as has been pointed out, in order to increase the amount of the primary winding the present invention provides for the introduction of a multiplying mechanism between the primary cam and 55 the tripping mechanism. This multiplying mechanism comprises a rotary member 82 journaled on a stud 83 secured to and projecting laterally from the arm 30 of the bracket 25. This rotary member or multi-

plier comprises a ratchet wheel 84 and a pin wheel 85. The ratchet wheel is formed with any suitable number of teeth 86, eight of such teeth being illustrated as a convenient number, projecting within the path of pins 87 which are secured to the primary 70 cam 34 and extend through openings 88 in the web of the secondary cam 35, which preferably is a skeletonized structure. The pins 87 are conveniently provided with integral collars 89 near their bases adapted to rest 75 against the inner surface of the cam 34 and the stems of the pins extend through slots 90 in the cam, and are firmly secured to the cam by nuts 91. The pins 87 may thus be adjusted longitudinally of the slots 90 so 80 as to strike the ratchet teeth 86 at the required position in the rotation of the cams.

The number of lobes of the cams may be varied but structural limitations render four lobes, as indicated, a desirable number. 85 There may be a pin 87 for each lobe or any lesser number may be employed. As each pin during the rotation of the cams comes into the path of the multiplier it strikes one of the ratchet teeth 86 and moves the multiplier one step. According, therefore, to the number of pins mounted in the cam is the number of steps which the multiplier will be rotated in one rotation of the cam.

The pin wheel 85 of the multiplier is provided with a series of holes 92 corresponding in number to the teeth and pins 93 are provided which may be locked in the holes 92 by set screws 94 so as to project laterally from the pin wheel. The path of these pins 100 intersects the path of a portion 95 of the pivoted latch 76 so that as a pin 93 is moved by the rotation of the multiplier against the latch 76 the latch will be swung out of engagement with the dog 80 thus releasing the 105 rod 63 to actuation by the spring 64. The number of pins inserted may vary from one to the full number. It will thus be seen that by varying the number of these pins and by varying the number of the pins 87 110 in the cam the latch may be operated to produce almost any number of traverses of primary winding up to the maximum number which would be produced by a single pin in each.

Overthrow or reverse rotation of the multiplier is prevented by a detent pawl 96 pivoted on the pin or shaft 78. The engagement of the detent pawl 96 with the ratchet wheel and of the latch 76 with the dog 80 is 120 further maintained against jar or vibration by a coiler contractile spring 97 connected at its ends to arms 98 and 99 upstanding respectively from the pawl and the latch.

In order to provide for the release and removal of the primary cam 34 from its operative position at the conclusion of a downward traverse means are provided for that pur-

pose. This is accomplished by providing the primary and secondary cams with coincidently curved surfaces adapted to engage the builder arm so that so long as these 5 coincident surfaces are engaged the weight of the builder arm and other mechanism connected therewith will prevent the axial movement of the primary cam 34 upon the cam shaft 35. Suitable depressions are made 10 in the surface of the primary cam 34 to permit the shifting thereof at predetermined points. In the construction illustrated the primary cam 34 is provided with lobes 100 having portions 101 coincident with like 15 portions of the lobes 102 of the secondary cam 35. Slight depressions 103, 104, 105 and 106 are provided in the surface of the cam 34 adjacent to the apices of the lobes 102 of the cam 35 so that when the apices of the 20 cam 35 come into engagement with the builder arm, after the latch 76 is released from its engagement with the dog 80, the spring 64 will force over the lever 68 carrying with it the primary cam 34 out of operative relation to the builder arm, whereby 25 subsequent movement of the builder arm will be effected through the secondary cam 35 alone.

The apparatus is illustrated as set up for 30 winding ordinary bobbins with a bunch and also with the maximum number of windings permissible with this specific construction. For that purpose one pin 87 is used in the cams and but one 93 in the multiplier. In 35 winding a bunch it makes no difference at which end of the slot 90 the pin 87 is set. By varying the number of pins 87 and the number of pins 93 any number of traverses less than the maximum may be secured.

40 When it is desired to wind a feeler slotted bobbin then the multiplier is filled with pins 93 and each slot 90 is provided with a pin 87. The length of the slot 90 is such that if the pin 87 is placed in the forward end of 45 the slot (in the direction of travel) the builder arm will be given an upward and downward traverse, while if it be placed in the rearward end a simple downward traverse will result. For example (referring to 50 Fig. 7) if the pin 87 is set in the forward end of the slot as shown and movement was beginning with such an angular position of the cam that pin 87 would be the next to contact with the multiplier pins 93, then the 55 pin 87 would actuate the multiplier, and consequently trip the latch 76 before the depression 106 reached the follower 24. Consequently when the depression 106 reached the follower 24 the follower would be engaged only by the lobe 102 of the secondary 60 cam and the spring 64 acting through the rod 63 would force the primary cam out of operative relation to the builder arm. If, however, the pin 87 were at the rearward end

of the slot 90 it would not operate the multiplier until after the depression 106 had passed the follower 24 so that the counterweights on the levers 10 would maintain the follower upon the builder arm in contact with the primary cam, thus preventing the lateral shifting of the primary cam and causing it to actuate the builder arm until the depression 103 is reached. Thus by adjustment of the pin 87 to one or the other ends of its slot the primary cam will actuate the 75 builder arm to cause a downward traverse or a downward, upward and downward traverse before the primary cam is shifted out of operative relation to the builder arm. By this means and by various combinations 80 of the pins the desired plurality of layers of primary winding will be placed upon the bobbin starting with a downward traverse thus adapting the bobbins for use in looms of any width. 85

When the mechanism is used for the winding of a bunch upon a regular bobbin it is necessary to insure that the desired taper shall be given at each end of the bunch. This tapering of the bunch is effected in a 90 well known manner by a step by step operation of the winding mechanism to let off the chain 15 to effect the gain of the traverse, whereby the ring rail rises a little higher on each successive up stroke and descends not 95 quite so far on each successive down stroke. The pick mechanism must be operated by the oscillation of the builder arm whichever one of the cams 34 and 35 is in action, but when the primary cam 34 is acting the amplitude 100 of oscillation of the builder arm is so small that it is insufficient to impart the requisite running off to the chain 15 to provide the proper gain, and accordingly, means are provided in connection with this invention 105 which act during the primary winding to make up the deficiency in the gain due to the short stroke of the builder arm.

The operation of the pick mechanism is secured by the pick pawl 22 being brought 110 into contact with a pawl actuator. The main pawl actuator is illustrated as an arm 107 projecting down from and vertically adjustable at 108 in the bracket 26. Upon the up stroke of the builder arm the pawl 22 115 strikes against the lower end of the arm 107 and according to the vertical adjustment of the arm 107 the desired pick motion is given. When, however, the movement of the builder arm is slight, as when making 120 the primary traverse, it is necessary in order to secure operation of the pawl 22 to bring into play an auxiliary pawl actuator 109. This actuator 109 is shown as a similar arm 125 vertically adjustable at 110 in a head 111 pivoted at 112 to the bracket 26. The head 111 is weighted at 113 so that the auxiliary pawl actuator 109 is swung thereby to the

right (viewing Fig. 2) and out of the path of the pawl 22. The rod 63 is provided with a collar 114 carrying a beveled dog 115 co-operating with a lug 116 extending laterally from the head 111 and so arranged that when the dog is slid over the lug 116 the arm 109 will be swung back against the action of the weight 113 into vertical position and into contact with a stop lug 117 on the main pawl actuator 107.

The operation of the pawl actuator will now be clear. When the primary cam 34 is thrown into operative position by the movement of the rod 63 to the left the dog 115 riding over the lug 116 forces the auxiliary pawl actuating arm 109 into vertical position and locks it there as shown in Figs. 2 and 7. When at the completion of the primary winding the trip mechanism acts 20 and the rod 63 is released and moves to the right the dog 115 rides off from the lug 111 and the arm 109 swings under the actuation of the weight 113 out of position and the main pawl actuating arm 107 is left to effect the actuation of the pick motion.

The general operation of the mechanism will also be apparent from the foregoing description. A slight depression of the foot lever 56 first operates to cause the cam 52 to move the shipper 45 to the left (Fig. 6) thus disengaging the clutch. Then the bifurcated end 75 of the shipper operates against the collar 65 and further depression of the foot lever causes the rod 63 to move 35 to the left and bring the primary cam 34 into operative position as shown in full lines in Fig. 6. At the same time the inclined surfaces 61 and 62 engage the positioning studs 40 on the disk 38 and thereby 40 rotate the primary and secondary cams to a starting point so that the initial movement to the builder arm under the influence of the primary cam shall effect a short slow downward traverse. When the rod 63 reaches the limit of its movement toward 45 the left the latch 76 rides over and drops behind the dog 80 thus retaining the primary cam in operative position. At the same time the dog 115 rides up onto the lug 50 116 swinging the auxiliary pawl actuating arm 109 into operative position. Upon the release of the lever 56 the spring 46 forces the clutch 41 into engagement with the disk 38 and upon the starting of the machine 55 the cams rotate. When the pin or pins 87 in the cams have caused the operation of the multiplier in a manner described and according to the particular adjustment the latch 76 is tripped releasing the rod 63 so 60 that the spring 64 acts to force the rod 63 to the right. Such movement cannot, however, be effected so long as the follower 24 of the builder arm is in engagement with an operative surface of the primary cam.

There is, however, sufficient lost motion in 65 the connections to allow a slight movement of the rod 63 thus preventing the latch 76 from again catching the dog 80. But when the proper recess or depression in the periphery of the primary cam comes opposite 70 to the follower 24 the follower is thereby retained out of contact with the primary cam and under the influence of the spring 64 the primary cam is immediately forced to the right and out of operative position. 75 At the same time the auxiliary pawl actuating arm 109 is released and swings out of operative position.

Having fully described our invention, what we claim as new and desire to secure 80 by Letters Patent is:

1. Builder mechanism for spinning machines comprising a builder arm, a cam shaft, a primary and a secondary traverse cam mounted upon and rotated in unison by 85 said shaft to actuate said builder arm, spring actuated means tending normally to move said primary traverse cam out of operative relation to said builder arm, a latch to maintain said primary traverse cam in operative 90 relation to the builder arm, multiplying means for releasing said latch, means carried by said primary traverse cam for actuating said multiplying means, whereby said latch may be released at a predetermined 95 point in the first or a predetermined subsequent rotation of the said primary traverse cam.

2. Builder mechanism for spinning machines comprising a builder arm, a cam 100 shaft, a primary and a secondary traverse cam mounted upon and rotated in unison by said shaft to actuate said builder arm, spring actuated means tending normally to move said primary traverse cam out of operative 105 relation to said builder arm, a latch to maintain said primary traverse cam in operative relation to the builder arm, a rotary multiplier rotated step by step from said primary traverse cam and provided 110 with a plurality of circumferentially disposed pin seats, one or more pins located in said seats as required with their path of rotation intersecting said latch whereby said latch may be released upon the completion 115 of a predetermined amount of primary winding.

3. Builder mechanism for spinning machines comprising a builder arm, a pick motion carried by said builder arm, a cam 120 shaft, a primary and a secondary traverse cam mounted upon and rotated in unison by said shaft to actuate said builder arm, spring actuated means tending normally to move said primary traverse cam out of operative 125 relation to said builder arm, a latch to maintain said primary traverse cam in operative relation to the builder arm, multiply-

ing means for releasing said latch, means carried by said primary traverse cam for actuating said multiplying means, whereby said latch may be released at a predetermined point in the first or a predetermined 5 subsequent rotation of the said primary traverse cam, and auxiliary means moved into and out of operative position upon the setting and releasing respectively of said latch to engage and operate the pick motion during the control of the builder arm by the primary traverse cam.

4. Builder mechanism for spinning machines comprising a builder arm, a pick motion carried by said builder arm, a cam shaft, a primary and a secondary traverse cam mounted upon and rotated in unison by said shaft to actuate said builder arm, spring actuated means tending normally to move 10 said primary traverse cam out of operative relation to said builder arm, a latch to maintain said primary traverse cam in operative relation to the builder arm, a rotary multiplier rotated step by step from said primary 15 traverse cam and provided with a plurality of circumferentially disposed pin seats, one or more pins located in said seats as required with their path of rotation intersecting said latch whereby said latch may be 20 released upon the completion of a predetermined amount of primary winding, and auxiliary means moved into and out of operative position upon the setting and releasing respectively of said latch to engage and 25 operate the pick motion during the control of the builder arm by the primary traverse cam.

5. Builder mechanism for spinning machines comprising a builder arm, a pick motion carried by the builder arm, means for actuating said builder arm to effect a primary winding of short, slow traverse, means operable upon the completion of one or more short slow primary traverses to actuate 40 said builder arm to effect a service winding of relatively longer and more rapid traverse, auxiliary means moved into and out of operative position with respect to the pick motion upon the beginning and ending 45 respectively of the primary winding to engage and operate the pick motion to produce gain during the primary winding, means for positioning the builder arm actuating mechanism to a starting point which 50 will cause an initial downward traverse of the yarn upon the bobbin whereby either a feeler slotted bobbin may be wound with an initial downward traverse and one or more additional short traverses all below the 55 feeler portion of the slot or any kind of bobbin may be wound with a tapered bunch as desired.

6. Builder mechanism for spinning machines comprising primary and secondary

traverse cams, means acting to force the 65 primary cam out of operative position, a latch for holding said primary cam in operative position, a rotary multiplier mounted adjacent said latch and given a step by step rotation from said primary cam, a plurality of circumferentially disposed pin 70 seats in said multiplier, pins located in said seats with their path of rotation intersecting said latch whereby according to the number of pins inserted in the pin seats the timing of the releasing of the latch and consequently of the period of operation of the said primary cam may be determined.

7. Builder mechanism for spinning machines comprising primary and secondary 80 traverse cams, means acting to force the primary cam out of operative position, a pick motion, an auxiliary pick motion actuator, means for forcing said actuator out of operative position, a latch for holding said 85 primary cam in operative position and said auxiliary actuator in operative position, a rotary multiplier mounted adjacent said latch and given a step by step rotation from said primary cam, a plurality of circumferen- 90 tally disposed pin seats in said multiplier, pins located in said seats with their path of rotation intersecting said latch whereby according to the number of pins inserted in the pin seats the timing of the releasing of the 95 latch and consequently of the period of operation of the said primary cam and of said auxiliary actuator may be determined.

8. Builder mechanism for spinning machines comprising primary and secondary 100 traverse cams, a spring actuated sliding rod for forcing the primary cam out of operative position, a pick motion, an auxiliary pick motion actuating pivoted arm normally swung out of operative position, a 105 pivoted latch, a dog carried by said rod coöperating with said latch, a second dog carried by said rod coöperating with said auxiliary pick motion actuating arm, whereby when the rod is retracted against its spring to bring the 110 primary cam into operative position the first dog will be engaged by the latch to lock the rod and the second dog will engage the auxiliary pick motion actuating arm and move it into and lock it in operative position, and 115 means for releasing the latch actuated from the primary cam.

9. Builder mechanism for spinning machines comprising primary and secondary 120 traverse cams, a spring actuated sliding rod for forcing the primary cam out of operative position, a pick motion, an auxiliary pick motion actuating pivoted arm normally swung out of operative position, a pivoted 125 latch, a dog carried by said rod coöperating with said latch, a second dog carried by said rod coöperating with said auxiliary pick motion actuating arm whereby when the rod is

retracted against its spring to bring the primary cam into operative position the first dog will be engaged by the latch to lock the rod and the second dog will engage the auxiliary pick motion actuating arm and move it into and lock it in operative position, a rotary multiplier for releasing the latch, said multiplier rotated step by step from the primary cam and provided with a plurality of circumferentially disposed pin seats, one

or more pins located in said seats as required with their path of rotation intersecting said latch whereby said latch may be released by the primary cam at a predetermined time.

In testimony whereof, we have signed our names to this specification.

HARRY F. HAWKINS.
MYRON L. STICKNEY.
